SOFA OR SIMILAR ARTICLE

Lawrence Peabody, Rindge, N. H., assignor to Kroehler
Mfg. Co., Naperville, Ill., a corporation of Illinois

Application November 17, 1955, Serial No. 38,938

Term of patent 14 years

(Cl. D15—11)

Fig.1.

Fig.2.

Fig.3.

Fig. 1 is a front perspective view of a sofa or similar article showing my new design;

Fig. 2 is a side perspective view thereof; and

Fig. 3 is a fragmentary top plan view of an end portion thereof.

The side of my sofa or similar article opposite that shown in the figures is symmetrically reverse but otherwise identical.

The characteristic features of my design reside in the arm rest portion of the end sections of the sofa, in their relation to and association with the other portions all as shown.

I claim:

The ornamental design for a sofa or similar article, as shown and described.
